Ernest M. White

By
Edward J. House

UNITED STATES PATENT OFFICE.

ERNEST M. WHITE, OF LOS ANGELES, CALIFORNIA.

GAS-MIXING DEVICE.

1,426,695.

Specification of Letters Patent. Patented Aug. 22, 1922.

Original application filed July 8, 1919, Serial No. 243,917. Divided and this application filed April 18, 1921. Serial No. 462,420.

To all whom it may concern:

Be it known that I, ERNEST M. WHITE, a citizen of the United States, residing at Los Angeles, in the county of Los Angeles, State 5 of California, have invented new and useful Improvements in Gas-Mixing Devices, of which the following is a specification.

My present invention is a division of my allowed application entitled "Homogenizer", bearing Serial Number 243,917, filed 10 July 8th, 1919, and relates to a device for mixing gases, which is particularly adapted to be used in conjunction with an internal combustion engine for effecting a more perfect mixture of the oil and air before the mixture enters the engine, and is especially effective when heavy oils which are more difficult to mix are supplied to the carburetor, such oils being liable to separation from 15 the mixture when passing from the carburetor to the engine.

A further object of my invention is to provide a device which may be mounted in different positions with respect to its intake and outlet ports, without impairing its 20 efficiency, in order that it may be readily and conveniently applied to engines of various makes.

Other objects will be more fully disclosed 25 in the following description, will be pointed out in the claims, and will be embodied in the accompanying drawings, in which:

Fig. 1 is a sectional view through a casing embodying my invention.

Fig. 2 is a similar view showing the casing as placed in a different position to that of Fig. 1.

My device comprises a suitable casing 5, preferably formed of a casting, and provided 30 with a mixing chamber 6 having a water jacket 7 formed therearound. The casing 5 is provided with a passage 8 through which the gas from the engine carburetor (not shown) enters the chamber 6, and a port 9 35 through which the re-mixed gas charge passes to the gas intake manifold 10 of the engine.

The chamber 6 consists of a semi-annular passage 11 which increases in area from its 40 intake end to its discharge end in order that the gases will expand and a centrifugal action will set up upon the fluid passing therethrough, said discharge end communicating with the suction port 9 which is of

lesser area than the same, and a dead air 55 pocket 12 formed in chamber 6 which is separated from intake passage 8 by a wall or baffle plate 13. A narrow passage 14 is formed in the wall 13 to provide communication between the discharge end of the annular passage 11 and the inner end of intake passage 8.

The gas intake end of passage 8 is contracted to form a throat as at 15 in order that the velocity of the gases passing into 65 said passage past the passage 14 will be increased, and a gas admission regulating valve 16 may be interposed between passage 8 and the carburetor as shown in Fig. 1 of the drawings.

A circulation of a heated fluid in the jacket 7 may be had through the pipe connections 17 and 18, in order to heat the mixing chamber to aid in the volatilization of 70 the gases.

In the operation of my device, suction is created in the usual manner, by means of the piston of the engine, which causes the gas mixture to be drawn from the carburetor through the passage 8 thence through 75 the semi-annular passage 11 out through the port 9 to the engine cylinder. As the mixture passes through passage 11 with a whirling motion it is allowed to expand and become separated, the heavier or more volatilized 80 particles of the oil are thrown by centrifugal action outwardly toward the outer surface of the wall of passage 11, and substantially tangent thereto, and by momentum and gravity are thrown against the wall 13, 85 90 the lighter and more thoroughly mixed portions of the vaporized mixture passing through the port 9 to the engine cylinders to perform its usual function. As the mixture from the carburetor passes by the contracted portion 15 of passage 8, it increases 95 in velocity thereby acting to suck the heavier particles of the mixture which have accumulated on wall 13 through passage 14 together with a portion of the gaseous mixtures passing through passage 11, to again 100

be whirled through said passage and be broken up and become more volatile and intimately mixed.

When the device is assembled with respect 105 to the engine and carburetor to assume the position shown in Fig. 1, the top surface of the wall 13 is inclined downwardly and in-

wardly toward the passage 14 thereby causing the heavy oil particles to flow toward said passage to be drawn therethrough.

When it is desired to assemble the device 5 in a position such as is shown in Fig. 2 of the drawings the breaking up of the heavy particles of the oil and the remixing operation is substantially the same as that above described, the heavy oil particles being 10 thrown against the wall 13 and that portion of the same which is not at once drawn through the passage 14, dripping downwardly into chamber 12 and passing through a channel 20 formed in the casing 15 casting and thence to the passage 8 to be again mixed with the incoming vapor and broken up as previously described.

In the drawings the general direction of the flow of the particles of the mixture is indicated by the arrows, the arrow "A" indicating the volatile or light gases, the arrow "B" indicating the heavy particles or less volatile part of the gases and the arrow "C" the direction of the gases and heavy 25 particles of the mixture through the passage 14 to become re-mixed with the incoming gases from the carburetor.

What I claim is:

1. A gas mixing device, comprising a casing 30 provided with a semi-annular passage communicating at one of its ends with an intake passage and at its other end with a discharge port, said semi-annular passage having its ends connected by a communicating passage of smaller area than the area thereof.

2. A gas mixing device, comprising a casing 40 provided with a semi-annular passage communicating at one of its ends with an intake passage and at its other end with a discharge port and a dead air pocket, the intake end of said semi-annular passage be-

ing connected to said dead air pocket by a communicating passage of smaller area than said semi-annular passage. 45

3. A gas mixing device, comprising a casing provided with a semi-annular passage communicating at one of its ends with an intake passage and at its other end with a discharge port and a dead air pocket, said semi-annular passage increasing in area 50 from its intake end to its discharge end, the intake end of said semi-annular passage being connected to said dead air pocket by a communicating passage located at the intersection of said intake passage and the intake 55 end of said semi-annular passage.

4. A gas mixing device, comprising a casing provided with a semi-annular passage communicating at one of its ends with an 60 intake passage and at its other end with a discharge port, said semi-annular passage having its ends connected by a communicating passage of smaller area than the area thereof and said intake passage being contracted to form a throat adjacent its outer 65 end.

5. A gas mixing device, comprising a casing 70 provided with a semi-annular passage communicating at one of its ends with an intake passage and at its other end with a discharge port and a dead air pocket, said semi-annular passage having its ends connected by a communicating passage of smaller area than the area thereof and said intake 75 passage being contracted to form a throat adjacent its outer end, said dead air pocket having a drain port communicating therefrom to said intake passage adjacent its outer end. 80

In witness that I claim the foregoing I have hereunto subscribed my name this 5th day of April, 1921.

ERNEST M. WHITE.
